DESIGN FOR A DRESS ENSEMBLE

Joe Kipness, New York, N. Y., assignor to Joe Kipness, Inc., a corporation of New York

Application June 26, 1947, Serial No. 139,935

Term of patent 3½ years

(Cl. D3—26)

To all whom it may concern:

Be it known that I, Joe Kipness, a citizen of the United States of America and a resident of the city of New York, in the county of New York and State of New York, have invented a new, original, and ornamental Design for a Dress Ensemble, of which the following is a specification, reference being had to the accompanying drawing, forming a part thereof.

Fig. 1 is the front view of a dress ensemble showing my new design.

Fig. 2 is a rear view thereof.

Fig. 3 is a front view of the dress member of the dress ensemble shown in Fig. 1.

Fig. 4 is a rear view thereof.

I claim:

The ornamental design for a dress ensemble, substantially as shown.

JOE KIPNESS.
